DESIGN FOR AN ARCHER'S GLOVE

Fred B. Bear, Detroit, Mich.

Refiled for abandoned application Serial No.
D-62,709, May 18, 1936. This application filed
September 17, 1937, Serial No. D-71,660

Term of patent 14 years

To all whom it may concern:

Be it known that I, Fred B. Bear, a citizen of the United States, residing at Detroit, in the county of Wayne and State of Michigan, have invented a new, original, and ornamental Design for Archers' Gloves, of which the following is a specification, reference being had to the accompanying drawing, forming part thereof, wherein:

Fig. 1 is a perspective view of the glove, showing its outer face.

Fig. 2 is a perspective view, showing the inner face of the glove.

The present application is a substitute for my application filed May 18, 1936 under Serial No. D-62,709.

I claim:

The ornamental design for an archer's glove as shown.

FRED B. BEAR.
